MARTIN D. MIESNER, OF WITTENBERG, MISSOURI.

COMBINATION TABLE AND BED.

1,274,431.

Specification of Letters Patent.

Patented Aug. 6, 1918.

Application filed July 11, 1918. Serial No. 108,627.

To all whom it may concern:

Be it known that I, MARTIN D. MIESNER, a citizen of the United States, residing at Wittenberg, in the county of Perry and

5 State of Missouri, have invented certain new and useful Improvements in Combination Tables and Beds, of which the following is a specification.

This invention relates to an improvement 10 in a combination table and bed, and more particularly to the manner in which the parts of the table are connected together to permit the desired opening and closing of the same in adapting the device for use as a bed 15 and also for use as a table, together with the means by which the bed structure is supported when the device is adjusted to be used as a bed.

An object of my invention is to provide 20 means by which when the table top is closed down it will be automatically swung to a partly open relation as the device is to be used as a bed, and when the bed is being used and it is desired to readjust the parts 25 to form a table, the table top will be swung to a partly closed relation, it being of course understood that means is provided to hold the parts in the closed relation and again in the full extended relation as when the device 30 is to be used as a bed.

A further object is to construct parts of the device in such a manner that the web spring structure of the bed is permitted to be folded to come within the upper portion 35 of the table as the top is closed down so that the device may be used as a table, and the spring structure will be extended after the top of the table is raised to form the head extension.

40 Yet another object is to so arrange the support for the extensible foot portion of the spring structure that as the parts are brought to the folded relation this support will be inclosed within the upper portion of 45 the table and as the support is opened to occupy the supporting relation a foot extension will be carried out to give greater length to the spring structure.

With the above and other objects in view, 50 my invention consists in certain novel features of construction and combinations of parts which will be hereinafter set forth in connection with the drawings and then more particularly pointed out in the claims.

55 In the drawings:

Figure 1 is a view in perspective showing the table top raised and the spring structure for the bed in the extended and operative relation.

Fig. 2 is a transverse vertical sectional view through the table structure with the parts thereof shown in substantially the approximate relation to which they will be thrown automatically upon release of the means by which the table top is held down 60 in the closed relation or the means by which this top is held in a relation to permit use of the device as a bed, the relation of the parts as shown in Fig. 1 being indicated by the dotted lines. 65

Fig. 3 is a sectional view similar to Fig. 2 but showing the top closed and the parts of the structure in the folded relation. 70

Fig. 4 is a fragmentary detail view to show the manner of connecting and operating 75 the foot extension.

The supporting structure comprises the ends 1 and 2 which comprise the legs 3 having cross members 4 secured therebetween, and the longitudinally extending frame 80 members 5 are connected between the end frame members 1 and 2 to connect the structure in a rigid frame.

The opposed legs of each pair are cut away at their upper ends to form the blocks 6 and 85 7, which are hinged as indicated at 8 so that they can be swung up to form substantially continuations of the posts or legs 3, as is shown in Fig. 3, or are capable of swinging movement to a lowered position as shown in 90 Figs. 1 and 2. A table top 9 is connected with the blocks 6 of each of the end members 1 and 2, and thus a substantially L-shaped formation is provided as is better shown in Fig. 2, which structure portion is permitted 95 to have, swinging movement around the hinged mounting at 8 so that it can be either closed to the relation shown in Fig. 3 or opened to the position shown in dotted lines in Fig. 1. Rim extensions 10 and 11 are 100 provided at each end of the top 9 and a like extension 12 is provided on the free edge, the space between the blocks 6 being filled in by a board or rim extension 13, and the end members 1 and 2 being provided with filler 105 boards 14 and 15 which form substantially continuations of the rim portions 10 and 11 at the ends of the frame structure and between the upper ends of the posts or legs 3. The blocks 7 have a board or rim member 110

- 16 connected therebetween so that these blocks are held to swing together and when brought to the interfitting relation with the shaped upper ends of the posts 3 with the 5 top 9 closed down, this rim member 16 with the like members 13, 14 and 15 will form a substantially box-like inclosed space in the upper portion of the frame and below the top 9.
- 10 A latch lever 17 having the end thereof hooked is pivotally mounted on the member 16 and a spring 18 is provided to engage beneath the free end thereof to normally force this latch lever into spring held engagement 15 with the latch hook 19 carried by the rim portion 12 of the top 9, and thus as the top is lowered and the latch lever 17 engages with the latch hook 19 to be held under the spring tension, the top will be not only 20 brought down against the post in a proper fitting relation, but the parts will be retained in this position against casual displacement and will be so held until the latch lever 17 is manually released against the tension of 25 the spring 18. When the parts are brought to the folded position as shown in Fig. 3, the only visible evidence of the fact that a folding table is provided is the fact that the blocks 6 and 7 are cut from the tops of the 30 posts 3, and by the mounting of a scrolled ornament on the blocks 6 and 7 or on the posts 3 adjacent to the cut away portions thereof, this cutting of the posts can be very effectually disguised and then the evidence 35 of the folding mounting of the parts will be carried only by the hinges, it however being understood that these can of course be very well disguised by being finished to match the finish of the wood work of the table, and 40 also perhaps by being set into the blocks and the posts so that the butts will be only partly visible. These features of decoration which are intended to disguise the true nature of the table so that it can be used as an ordinary 45 library or other table will of course fall within the perview of the manufacturer, and for this reason these features are not here shown and are not discussed at great length.
- 50 The spring frame of the bed structure is made up preferably of angle iron members, and the members 20 and 21 are connected rigidly on the inner sides of the end members 1 and 2, so that they will be confined 55 and inclosed within the space covered by the rim portions 14 and 15 of these end members. Uprights 22 are secured on the inner sides of the rim members 14 and 15 adjacent to the ends connected with the posts on 60 which the blocks 6 are hingedly mounted, and the levers 23 and 24 are pivotally mounted as at 25 on these upright members 22, and have pins 26 carried by their free outer ends to be received and slide in the 65 slotted guides 27 secured on the rim mem-
- bers 10 and 11. The shortened ends of the levers 23 and 24 are pivotally connected with the bars 28 which are extended on each side of this pivotal mounting, and the coil springs 29, of which I have shown two 70 mounted on each end of the bars 28 are connected at their free ends with the side members 20 and 21 of the spring supporting frame. By this arrangement of the parts, the drawing tension exerted upon the bars 75 28 is made quite severe due to the fact that the four springs connected with each bar are working practically together and consequently the tendency of the springs is to swing the levers 23 and 24 around a pivotal 80 mounting at 25 on the upright 22 so that the pins 26 thereof will be moved along the slots of the guideways 27 to permit these levers 23 and 24 to occupy a vertically upright position as shown in Fig. 2 and in consequence 85 the blocks 6 and the top member 9 will be swung around the mounting on the hinges 8 to be raised to an intermediate position in accordance with the showing on Fig. 2. Notches 30 are provided in the members 27 90 at one side of the slotted openings thereof and the pins 26 are received in these notches 30 when the top 9 has been swung to the full open relation as indicated by the dotted lines in Fig. 2, in which fitting of the parts, the levers 23 and 24 will be held against return swinging movement under the tension of the springs 29 and consequently the top portion will be permitted to remain in the 95 open relation and will be supported against further swinging movement by the bracing 100 effects of the rods 23 and 24.
- A substantially U-shaped end spring frame member 31 has the inwardly bent ends thereof connected with the spring frame members 20 and 21 by the link members 32, and the supporting links 33 and 34 are connected with the levers 23 and 24 and at their other ends are connected with the U-shaped spring frame member 31 at substantially 105 the corners thereof. Stop rests 35 are provided on the frame links 32, and when the table top is brought to the full open relation, these stop rests engage against the blocks 6 and support the links against falling at their outer ends, this supporting 110 of the frame links 32 and the connection of the frame member 31 with the levers 23 and 24 through the medium of the supporting 115 links 33 and 34 acting to give the proper support to the spring frame extension structure.
- A substantially U-shaped spring frame member 36 is connected by the frame links 120 37 and 38 with the side spring frame members 20 and 21, and is thus capable of being folded over into the confines of the rim structure as formed in conjunction with the frame and the top of the table. The inwardly bent ends of the U-shaped spring 125 130

frame member 36 are provided with the elongated slots 39 and links 40 are connected with the blocks 7 and at their free ends through these elongated slots 39 so that as the member 36 is extended or folded, the blocks 7 and the rim member 16 mounted therebetween will be carried and supported in the opened or closed relation. The posts 3 adjacent to which the links 37 and 38 are 10 pivotally connected with the side spring frame members 20 and 21 are notched out and as the frame structure at the foot is opened, these links 37 and 38 will engage with portions of the post and will be held 15 against excessive downward swinging movement. The supporting legs 41 and 42 are pivotally mounted on the sides of the U-shaped frame member 36 adjacent to the corners thereof, and thus when the member 36 is extended, these legs 41 and 42 may 20 be swung down to rest upon the floor or other surface on which the legs or posts 3 of the table are supported and consequently the foot portion of the spring frame will be held in the proper extent with respect to the 25 remaining portions of the same. As will be seen by reference to Fig. 4 of the drawings, a foot extension 43 is pivoted on the U-shaped member 36 by means of the substantially bell crank shaped or L-shaped end 30 portions 44, and these L-shaped portions 44 have teeth formed as indicated at 45 adjacent to the pivotal mounting thereof, which teeth mesh with the teeth 46 of the legs 41 and 42. By providing the teeth at 45 and 46 and placing the same in mesh as the foot 35 extension portion 43 is opened, both legs 41 and 42 will be swung to the operative relation, or as either of the legs is swung to the supporting position the remaining leg will 40 be opened and simultaneously the foot extension will be brought to the operative relation. Some means, as for instance the stop lugs 47 might be provided to hold the foot 45 extension 43 against excessive swinging movement, and in this way the legs 41 and 42 will also be held against too great outward spread.

The bed spring structure may comprise 50 the wire mesh as indicated at 48 which may be connected directly with the side spring frame members 20 and 21, the end spring frame members 31 and 36, and the links 32, 37 and 38, to have a certain measure of flexibility embodied within its structure or may 55 be joined with this spring frame structure as described by the use of springs, or the webbing or mesh work of the springs may be connected with only certain of the frame members, as for instance the members 20, 21, 60 31 and 36, however, as this connection of the webbing or mesh structure of the springs with the frame does not constitute an essential part of my invention I have not herein 65 disclosed any specific construction.

In the use of the structure as a table, the top 9 will be folded over in the relation shown in Fig. 3, and the latch lever 17 is engaged with the latch hook 19 which holds the top down against the raising force exerted by the springs 29, and at the same time the swinging of the lever 23 to occupy a substantially horizontal position causes raising of the bars 28 and thus places a greater tension upon the springs 29. The 70 latch lever 17 will hold the parts in this closed relation against casual displacement or against displacement of the reaction of the springs 29, and thus the structure may be used as a table, and then when it is desired 75 to open the parts and extend the spring structure so that the device may be used as a bed, the latch lever 17 may be released by reaching beneath the rim member 16 and manually depressing the free end of 80 the latch lever 17 against the tension of the spring 18 which will disengage the hook end thereof from the latch hook 19 and consequently the top 9 will then be free and 85 will be swung up to the position shown in 90 Fig. 2 through the drawing tension exerted by the springs 29 on the levers 23 and 24. The top 9 is then grasped and given still further movement until the pins 26 are engaged in the notches 30 of the members 27 95 and in this relation the parts will be held until manually released. The link portions 32 are supported by the stop rests 35 in their engagement against the upper inner edges of the blocks 6 and the spring frame member 31 is supported by these links and also by the supporting links 33 and 34. The foot member 36 of the spring frame is then 100 grasped and swung outwardly and at the same time the extension portion 43 may be 105 swung over to be received against the stops 47 and the supporting legs 41 and 42 will be brought to the proper supporting relation, the abutment of the links 37 and 38 against the portion of the frame structure 110 acting to hold these links against excessive downward swinging movement and the connection of the ends of the frame members 36 with the free ends of the links 37 and 38 and with the legs 41 and 42 giving a full 115 support to this member 36. When the table is to be again folded, the frame member 36 may be swung upwardly and inwardly to carry the links 37 and 38 therewith and consequently the rim member 16 will be raised 120 through the carrying of the same by the links 40 which are received in the slots 39 of the member 36, and swinging movement of the extension foot member 43 will cause both of the legs 41 and 42 to be folded down 125 into proximity with the member 36, the pins 26 may be then disengaged from the notches 30 and in consequence the pins 26 will then be free to move along in the slotted guides 27 and the tension exerted by the 130

springs 29 will act to elevate the levers 23 and 24 to the vertically upright relation shown in Fig. 2, from which position the top 9 may be again folded down so that the 5 latch hook 19 will be engaged by the latch lever 17 and the parts will be again closed to and held in the relation that the device may be used as a table without evidences of the bed structure other than those as above 10 set forth. While I have not herein set forth the relation which would be occupied by the mattress, blankets, etc., comprising the covering for the springs, it will be apparent by reference to Fig. 3 of the drawings that a 15 sufficient space is left within the confines of the several spring members that the bed clothing can be left on the spring as the structure is folded and would occupy substantially the position indicated by the dotted lines in Fig. 3.

From the foregoing it will be seen that I have provided a bed structure which is embodied entirely within a table of substantially standard proportion, and in which 25 the spring supporting structure is arranged to be capable of extension as the table is uncovered or the top is swung open, this top being likewise mounted to permit the desired extension, and further it will be noted 30 that the movement of the parts in either direction is substantially automatic when the securing means for holding the bed structure in the extended relation is released, the operation of swinging the legs 41 and 42 35 being also somewhat automatically accomplished by the swinging of the foot extension 43 to the operative relation.

While I have herein shown and described only one specific form of the structure, it 40 will be understood that the design of the table might be varied in a great variety of ways to match up with various styles of interior finish or furniture, that other forms of securing means for holding the parts in 45 each of the operative relations might be adopted, and that other changes and modifications might be resorted to without departing from the spirit and scope of my invention, and hence I do not wish to be 50 limited to the exact disclosure but only to such points as may be set forth in the claims.

I claim:

1. In combination with a table having the 55 top thereof hingedly connected to be capable of opening and closing movement, a bed bottom, foldably mounted in conjunction with the table structure to have portions thereof moved by the swinging of the table top, and 60 means to normally exert tension to swing the table top to an intermediate position between the opened and closed positions thereof.

2. A combination table and bed comprising 65 a frame structure having a table top

hingedly mounted thereon, a bed bottom foldably mounted on the frame to be capable of extension to form a bed spring and to be folded within the confines of the table so that the top can be closed, levers mounted on 70 the ends of the frame structure and having sliding connection with the top portion, springs by which force is exerted upon the levers to normally resiliently urge the same to move to a position to raise the table top, 75 and supporting links connected with the levers and with portions of the bed bottom structure so that upon swinging movement of the levers to raise the top the connected portions of the bed bottom are extended. 80

3. A combination table and bed comprising a frame structure having a table top hingedly mounted thereon, a spring frame structure made up of a plurality of side pieces and having cross pieces at the ends 85 thereof foldably mounted on the frame, bed spring structure associated with the foldable frame and the parts being so mounted that when folded they are inclosed within the confines of the table so that the top can be 90 closed, levers mounted on the ends of the frame structure to be capable of rocking movement, a sliding connection between one end of each of said levers and the table top, springs connected with the remaining end 95 of each lever and having connection with fixed portions of the structure to thus normally resiliently urge the levers to an upright relation, and links connected with the levers and with portions of the spring frame 100 structure in such a manner that as the table top is raised by the springs connected therewith the frame will be extended.

4. A combination table and bed comprising a frame structure having supporting posts and with portions of the posts cut away to form blocks, hinges connecting said blocks to be swung into and out of fitted relations with the post, a top connected with the blocks at one side of said frame, to be 105 capable of swinging movement therewith and arranged to be swung to an open relation in which it is extended from the frame structure through the hinged mounting of the blocks thereon, a spring frame made to 110 have a plurality of side sections to permit folding thereof, portions of the spring frame being attached to the supporting frame, a connection from said hingedly mounted top to the end portion of the spring frame 115 mounted adjacent thereto, and means connected with the remaining end of the spring frame to support the same in an operative relation.

5. A combination table and bed comprising a frame structure having supporting posts and with portions of the posts cut away to form blocks, hinges connecting said blocks to be swung into and out of fitted relations with the post, a top connected with 120

125

130

- the blocks at one side of said frame to be capable of swinging movement therewith and arranged to be swung to an open relation in which it is extended from the frame structure through the hinged mounting of the blocks thereon, a spring frame made to have a plurality of side sections to permit folding thereof, portions of the spring frame being attached to the supporting frame, a connection from said hingedly mounted top to the end portion of the spring frame mounted adjacent thereto, means connected with the remaining end of the spring frame to support the same in an operative relation, and means by which the parts are supported in the open and in the closed positions.
6. A combination table and bed comprising a frame structure having supporting posts and with portions of the posts cut away to form blocks, hinges connecting said blocks to be swung into and out of fitted relations with the post, a top connected with the blocks at one side of said frame to be capable of swinging movement therewith and arranged to be swung to an open relation in which it is extended from the frame structure through the hinged mounting of the blocks thereon, a spring frame made to have a plurality of side sections to permit folding thereof, portions of the spring frame being attached to the supporting frame, a connection from said hingedly mounted top to the end portion of the spring frame mounted adjacent thereto, means connected with the remaining end of the spring frame to support the same in an operative relation, means by which the table top is secured in a closed position, and means by which the top is swung to an open position upon release of said holding means.
- 10 connection from said hingedly mounted top to the end portion of the spring frame mounted adjacent thereto, means connected with the remaining end of the spring frame to support the same in an operative relation, means by which the table top is secured in a closed position, and means by which the top is swung to an open position upon release of said holding means.
- 15 40
- In testimony whereof I affix my signature in presence of two witnesses.
- MARTIN D. MIESNER.
